United States Patent Office

Des. 203,714
Patented Feb. 8, 1966

203,714

REAR PROJECTION MACHINE

Lee Radfke, Park Ridge, Ill., assignor to Sawyer's Inc.,
Portland, Oreg., a corporation of Delaware

Filed Oct. 28, 1964, Ser. No. 82,348

Term of patent 14 years

(Cl. D61—1)

Fig. 3

Fig. 4

Fig. 5

FIG. 1 is a perspective view of a rear projection machine, showing my new design, the device being shown in its closed condition with the front, top and handle-equipped side showing;

FIG. 2 is a perspective view of a rear projection machine in its opened and operating condition;

FIG. 3 is a top plan view thereof taken from the top of FIG. 2;

FIG. 4 is a bottom plan view thereof taken from the bottom of FIG. 2;

FIG. 5 is a front elevational view thereof taken from the front of FIG. 2;

FIG. 6 is a side elevational view thereof taken from the handle-equipped side of FIG. 2;

FIG. 7 is a rear elevational view thereof taken from the rear of FIG. 2; and

FIG. 8 is a side elevational view thereof taken from the side opposite that shown in FIG. 6.

The essential features of my design are shown in full lines.

I claim:

The ornamental design for a rear projection machine, as shown and described.
